UNITED STATES PATENT OFFICE.

GILBERT W. GOODRIDGE, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

DESIGN FOR AN INSULATED CHAIN CONNECTOR.

47,917.

Specification for Design.

Patented Oct. 5, 1915.

Application filed July 14, 1915. Serial No. 39,912. Term of patent 14 years.

To all whom it may concern:

Be it known that I, GILBERT W. GOODRIDGE, a citizen of the United States of America, residing at Bridgeport, in the county of Fairfield and State of Connecticut, have invented a new, original, and ornamental Design for an Insulated Chain Connector, of which the following is a specification, reference being had to the accompanying drawing, forming part thereof.

Figure 1 is a side elevation of the connector, showing my new design; and Fig. 2 is an end elevation of the same.

I claim:

The ornamental design for an insulated chain connector, as shown.

GILBERT W. GOODRIDGE.

Witnesses:

H. M. WICHERT,
H. W. BADEAU.
